SIMILAR ARTICLE

Douglass R. Falkenberg, 20997 Westlake Road,
Rocky River, Ohio 44116

Filed May 10, 1967, Ser. No. 7,061

Term of patent 14 years

(Cl. D21—1)

FIG. 1 is a front view of a drapery tie-back holder or similar article showing my new design;

FIG. 2 is a side view thereof; and

FIG. 3 is a rear view thereof.

The essential features of the design reside in the full line portions of the drawing.

This is a continuation-in-part of design application Serial Number 3,869, filed Sept. 15, 1966, and now abandoned.

I claim:

The ornamental design for a drapery tie-back holder or similar article, as shown and described.
